Andrew Wilson,
ATTORNEY.

UNITED STATES PATENT OFFICE.

THOMAS H. GRANT, OF ENGLEWOOD, NEW JERSEY.

GOLF-CLUB.

1,343,998.

Specification of Letters Patent. Patented June 22, 1920.

Application filed November 4, 1919. Serial No. 335,728.

To all whom it may concern:

Be it known that I, THOMAS H. GRANT, a subject of the King of Great Britain, residing at Englewood, Bergen county, New Jersey, have invented certain new and useful Improvements in Golf-Clubs, of which the following is a specification.

My invention relates to golf clubs which are provided with wooden heads. And my 10 improvements are particularly directed to means for increasing the weight of the head without impairing its life or springiness, while the increased weight is so disposed as to give a correct natural balance to the club 15 in the player's hands, avoiding twisting or warping when the ball is addressed and struck. The particular means by which these and other desirable results are obtained I will now proceed to point out and explain.

20 In the drawings Figure 1 is a plan view partly in section of the head and part of the handle of my improved club; Fig. 2 is a side view of the same, looking to the left on Fig. 1; Fig. 3 is a front view, looking to 25 the right on Fig. 2; Figs. 4 and 5 are respectively a side view and an end view of the reinforcing weight, and Figs. 6 and 7 are respectively a side view and an end view of the wooden plug.

30 The same parts are designated by corresponding reference numerals in all the figures.

The head 1 is of a conventional form having a striking face 2 and an extended neck 35 which is bored to receive the usual handle 4, the neck being, preferably reinforced by suitable wrapping 5. From the front of the head I bore a hole in the same vertical plane in which the handle of the club is disposed, 40 but in a horizontal plane which is parallel to the ground when the club is held in its normal position to strike a ball. This hole is extended back until its main bore is but a short distance from the end of the handle 45 socket, and then the bore and the socket are connected by a small hole 7 so that there shall be a continuous opening from the end of the head to the end of its neck.

The bore 6 is then provided with a screw 50 thread 8, preferably throughout its entire length, and a wooden plug 9 is prepared which is provided with a thread complementary to the thread 8 of the bore 6.

A plug of lead 10 is formed in the bore 6 55 by turning the mouth of the bore 6 up and pouring molten lead into it. The channel 7

allows the air in the end of the bore 6 to escape up through the handle socket, so that the lead can completely fill the bore 6 without the formation of bubbles or air pockets 60 in the metal. The lead may be more firmly expanded in the bore 6 by tamping, if desired. The screw thread in the bore gives a secure anchorage to the lead, so that it can not be jarred loose or shaken out when 65 the club is in use.

When the lead has been properly packed in the bore 6, the wooden plug 10 is screwed into place, and, preferably glued fast, and its outer end is dressed off to form a continuous surface with the end of the club. Afterward the handle may be inserted in its socket, and properly secured therein and the reinforcing wrapping placed around the neck.

70 When the parts of the club have been thus assembled, the lead weight will be disposed in the vertical plane of the handle, so that there will be no tendency of the head to be overbalanced to either side of the 75 reinforcing weight. Also the lead weight will be disposed in the horizontal plane of impact between the head and the ball, as illustrated in Fig. 3, so that when the blow is delivered the club will strike true and will 80 not warve up or down, as it would do if the weight were too high or too low. Also, the weight being disposed longitudinally about 85 equally to either side front and rear of the point of impact with the ball, neither the 90 heel nor the toe of the club will be thrown forward out of a true line when the blow is delivered, as would be the case if the weight were distributed unequally in relation to the 95 point of impact.

The wooden plug is sufficiently long to continue substantially the same thickness of wood which exists between the face 2 and the lead 10, around the end or toe of the club; so that the body of wood, in front of, 100 behind, above and below the weight will be of approximately equal thickness and the liveliness of the club, which is dependent upon continuity of the wood will not be interfered with.

105 By these means I secure a wooden golf club which is substantially reinforced in weight while its balance is carefully maintained, its liveliness not sacrificed, and its appearance not marred by exteriorly attached plates or weights or unsightly irregularities.

It will be understood that the details of my improvements may be modified by the use of mechanical equivalents without departing from the spirit of my invention as claimed, and this will be well understood by those skilled in the art.

Having thus described my invention, what I claim and desire to secure by Letters Patent of the United States is:—

- 10 1. The combination, in a golf club, of a wooden head, having a weight socket disposed in the vertical plane of the handle and the horizontal plane of the normal position of the club in use, an elongated, unitary, reinforcing weight permanently fixed in said socket and evenly disposed longitudinally and laterally relative to the point of the impact of the club with a ball, and a wooden element closing the outer end of said socket.
- 15 2. The combination, in a golf club, of a wooden head, having a weight socket disposed in the vertical plane of the handle and the horizontal plane of the normal position

of the club in use, an elongated, cylindrical, unitary reinforcing weight permanently fixed in said socket and evenly disposed longitudinally and laterally relative to the impact point of the club with a ball, and a wooden plug closing the forward end of said weight socket, said weight and plug completely filling said socket.

3. The combination, in a golf club, of a wooden head, having a weight socket disposed in the vertical plane of the handle and the horizontal plane of the normal position of the club in use, an elongated, cylindrical, unitary, reinforcing weight provided with anti-withdrawal means in said socket and evenly disposed longitudinally and laterally relative to the impact point of the club with a ball, and a wooden plug closing the forward end of the said weight socket, said weight and plug completely and permanently filling said socket.

THOMAS H. GRANT.
